HORACE W. ASIRE, OF DAYTON, OHIO, ASSIGNOR TO GENERAL MOTORS RESEARCH CORPORATION, OF DAYTON, OHIO, A CORPORATION OF DELAWARE

MULTIPLE CARBURETOR CHARGE FORMING DEVICE

Application filed August 29, 1935. Serial No. 53,338.

This invention relates to charge forming devices for multicylinder internal combustion engines.

It is one of the objects of the present invention to secure more even distribution of fuel charge to the various engine cylinders, in order that the engine may start more readily and operate more efficiently. In the present invention this object is accomplished by providing a unitary structure adapted to be attached to the intake ports of the engine and comprising a plurality of carburetors, each directly communicating with an engine intake port, said structure having a common air inlet for all of the carburetors and a single operating member for controlling all of the throttle valves of the carburetors.

Further objects and advantages of the present invention will be apparent from the following description, reference being had to the accompanying drawings, wherein a preferred form of embodiment of the present invention is clearly shown.

In the drawings:

Fig. 1 is a plan view of the form of the present invention shown attached to an internal combustion engine which is partly in plan and partly in section;

Fig. 2 is a side elevation of the apparatus shown in Fig. 1;

Figs. 3 and 4 are sectional views taken respectively on lines 3-3 and 4-4 of Fig. 1, these views being on a larger scale than Figs. 1 and 2.

Fig. 5 is a modified form of primary carbureting device which may be substituted for the form shown in Fig. 3.

The drawings indicate an internal combustion engine having a plurality of cylinders 20, each provided with an inlet valve 21 and an exhaust valve 22. Each exhaust valve communicates with an exhaust outlet pipe 23 and each pair of intake valves 21 is served by a common intake pipe 24.

The unitary charge forming device which is adapted to be attached by screws 25 to the intakes 24, comprises an air manifold 30 which provides air passage having a common inlet 31 (see Fig. 4), and branches 32, each communicating with an engine intake port 24

and each provided adjacent the intake with a Venturi member 33, which is retained by a screw 34 and lock nut 35. Each branch 32 of the air manifold 30 has a constant level fuel reservoir 36 located directly above the Venturi member 33. A fuel duct 37, preferably cast integral with manifold 30, communicates with all of the reservoirs 36, having one end attached by a coupling 38 with a fuel supply pipe 39. The fuel reservoir 36 includes a wall which is common to a portion of the duct 37 and this wall is provided with a hole 40 leading into a recess 41, which is threaded to receive a valve seat member 42 having an opening 43 adapted to be closed by a valve 44. Valve 44 is carried by a lever 45 secured to a float 46 and supported by a pivot pin 47 supported by a reservoir cover plate 48 retained in position by screws 49. Within each float bowl 36 a duct 50 extends above the normal level of fuel and is in communication with a hole 51 in the throat of the Venturi member 33. Cover 48 provides a duct 52 for connecting the duct 50 with outside atmosphere. A fuel pipe 55 having at its lower end a fuel-metering orifice 54 communicates with the passage 52 and is threaded to the cover 48. The flow of air into the passage 52 is limited by an air-flow metering plug 56. When the cover 48 is assembled upon the float bowl 36 the throat of venturi 33 is placed in communication with outside atmosphere and with the fuel in the bowl 36.

Adjacent its outlet, each branch pipe 32 of the air manifold 30 is provided with a throttle valve 60, and all the valves are connected with a shaft 61 which can be operated by a single control arm 62.

Referring to Fig. 4, the common air inlet 31 is controlled by an automatic valve mechanism which comprises a valve frame 70 having an air inlet 71 and an outlet 72 communicating with the common air inlet 31. Adjacent the outlet 72 the frame 70 is provided with a valve seat 73, which can be closed by a valve 74 attached to a stem 75 having its upper end connected to a dash pot piston 76. Piston 76 slides within a cylinder 77 which is contained within a cylindrical recess 78 by a spring clip 79 which is attached to the frame 100.

70 by a screw 80 and spaced from the frame 70 by a spacing tube 81. A coil spring 82 interposed between a spring seat cup 83 and the head of the piston 76 tends to retain the valve 74 upon its seat 73. The valve 74 is opened automatically by the suction of the engine against the urge of the spring 82. The dash pot piston 76 prevents fluttering of valve 74 and stabilizes its position according to engine speed and throttle position. The piston 76 is provided with a central aperture 76' which permits the escape of air downwardly therethrough during upward travel of the piston. However during the downward travel of the piston, the aperture 76' is closed by the check valve 76'', as will be clear from viewing Fig. 4. Therefore the effect of the dash pot will be to damp the opening movement of air valve 74 to a much greater degree than the closing movement thereof. Thus when the throttle valves 60 are suddenly closed to idling position the air valve 74 is permitted to close quickly enough to maintain sufficient depression in the air manifold 30 to cause the proper rich fuel mixture to be drawn through the duct 50.

The automatic operation of the main air valve 74 is modified by a manually actuated lever 84 attached to a shaft 85, which extends across the valve frame 70 and carries within said frame a lever 86 having a forked end engaging a pin 87 attached to a vertically reciprocatable sleeve 88. Sleeve 88 is provided with a shoulder 89 for engaging the seat cup 83. It will now be clear that the operator may change the position of the lever 84 to vary the position of the sleeve 88 and seat cup 83 in order to vary the compression in the spring 82 and thereby vary the degree of opening of air valve 74 for a given depression in the air manifold 30. By increasing the compression of spring 82 less air is admitted through valve 74 for a given depression in the air manifold 30 and hence a richer fuel mixture is drawn into the engine whenever desired. The suction of the engine causes primary air to enter the plug 56 and liquid fuel to flow upwardly through the duct 55 and form an overrich mixture of air and fuel in duct 50 which is drawn into the venturi 33 and mixes with the flow of air through the branch 32. The float 46 operates in the usual manner to close the fuel inlet passage 43 and maintain the level of fuel in the bowl 36 substantially constant.

Fig. 5 illustrates a modified form of primary carbureting device which may be used with the air manifold 30 in place of the form shown in Fig. 3. In Fig. 5 the cover plate 90 of the float bowl 36 has a fuel well 91 and a fuel mixture duct 92 which registers with the duct 50 extending upwardly through the float bowl 36. Atmospheric air enters the restricted air inlet tube 93 which extends downwardly within the duct 92 leaving an annular

space 94 around the air inlet tube 93. A low speed fuel jet 95 leads from the bottom portion of the fuel well 91 into the annular space 94 while a larger high speed fuel jet 96 leads from the upper portion of said fuel well into said annular space. Fuel is conducted from the float bowl 36 upwardly into well 91 by the pipe 97 having at its lower end a fuel metering orifice 98 and having the two fuel outlet orifices 99 and 100 located approximately as shown in Fig. 5. The venturi 101 has an annular groove 102 which registers with the duct 50. A series of holes 103 form a communication between the upper portion of the groove 102 and the throat of the venturi 101. The lower half of the groove 102 forms a semi-annular well 104 which communicates with the center of the Venturi throat through the stand pipe 105.

The operation of the device of Fig. 5 is as follows:

At slow engine speeds, say that corresponding to a car speed of 15 miles per hour, the depression in the air manifold 30 will create a depression in duct 92 which in turn will cause air to enter the primary air inlet tube 93 and liquid fuel to be drawn up through pipe 97, out through low speed fuel orifice 99 into the well 91, and thence through the low speed fuel jet 95 forming a rich mixture of air and fuel in duct 50. This rich mixture is drawn through the holes 103 and there sprayed into the air passing through the venturi 101 to form a mixture of the proper proportions for the engine when running at the slower speeds. If now the throttle 60 be opened to cause the engine speed to materially increase, the increased depression in air manifold 30 and the increased air flow through the venturi 101 will greatly increase the depression in duct 92 which in turn will cause fuel to be drawn up into well 91 through both orifices 99 and 100 faster than it can flow out through the jet 95 and hence the fuel level in well 91 will rise until it also flows through the larger high speed jet 96. The combined fuel flow through both jets 95 and 96 is such as to maintain the proper fuel and air ratio to the engine at the higher speeds thereof.

Now if the throttles 60 be closed to materially reduce the engine speed while the fuel well 91 is full, the air flow through venturi 101 and primary air inlet 93 will be greatly reduced but the greater part of the fuel in well 91 will run out through a jet 95 by gravity and flow down through ducts 92 and 50 and fill the semi-annular well 104 since there will not be sufficient suction to cause this superfluous liquid fuel to enter holes 103 and pass to the engine. In other words when the throttles 60 are closed to reduce high engine speed to low engine speed the fuel well 91 dumps and fills fuel well 104. If now the throttles 60 be suddenly opened to accelerate the engine the fuel in well 104 is drawn out

through stand pipe 105 to greatly enrich the mixture passing to the engine for a few moments to give a quick acceleration to the engine. The well 104 therefore serves as an accelerating well and is filled by the dumping of well 91 each time the engine speed is materially reduced by closing the throttles. Thus the well 104 is always ready to deliver an accelerating rich mixture when the throttles 60 are suddenly opened.

An important feature of this primary carburetor is the extension of the primary air inlet tube 93 beyond both the fuel jets 95 and 96. Any variation in the flow of fuel through these jets due to turbulent effects in the air stream is thus avoided and hence more accurate and uniform metering of the liquid fuel obtained.

One of the important advantages of the present invention is that of more evenly distributing fuel charge to the various cylinders. Each engine intake port is provided with a carbureting device which is situated relatively close to the cylinder intake valves. Since there is very little chance of uneven distribution occurring between a pair of intake valves, it is evident that the distribution will be more uniform than in the case where a single carburetor is used to supply fuel charge to four or more cylinders.

Another advantage lies in the simplicity of structure, enabling the device to be assembled on an engine in a simple manner, and to be connected with the fuel line by only one pipe connection.

While the forms of embodiment of the present invention as herein disclosed, constitute preferred forms, it is to be understood that other forms might be adopted, all coming within the scope of the claims which follow.

What is claimed is as follows:

1. In a charge forming device for a multi-cylinder internal combustion engine having a plurality of intake ports, an air manifold having a branch leading to each engine intake port and a common main air inlet, a spring closed valve in said main air inlet which is opened to admit air according to the depression in said manifold, an individual carburetor for supplying fuel to each of said branches relatively close to said engine intake ports, a throttle valve in each branch on the engine side of the point of fuel admission, common means for concurrently actuating all of said throttle valves, and manual means whereby the operator may at will change the spring tension on said spring closed valve to vary the amount of air admitted to said manifold and hence equally vary the fuel and air ratio drawn into each of said engine intake ports.

2. In a charge forming device for a multi-cylinder internal combustion engine having a plurality of spaced intake ports, an air mani-

fold having a branch leading to each engine intake port and a common main air inlet, a spring closed valve in said main air inlet which is opened to admit air according to the depression in said manifold, an individual primary carburetor associated with each manifold branch, said carburetor being located closely adjacent to the engine intake port, and adapted to supply an overrich mixture of fuel and air to its associated manifold branch close to said port, a throttle valve in each manifold branch for controlling the flow therethrough, and common actuating means for said throttles.

3. In a charge forming device for a multi-cylinder internal combustion engine having a plurality of spaced intake ports, an air manifold having a branch leading to each engine intake port and a common main air inlet, a spring closed valve in said main air inlet which is opened to admit air according to the depression in said manifold, a plurality of individual carburetors, one for each branch of the manifold and each of which is provided with a constant lever fuel chamber, said carburetors being located closely adjacent the engine intake ports and adapted to supply a mixture of fuel and air to the manifold branches close to said ports, a throttle valve in each manifold branch for controlling the flow therethrough and common actuating means for said throttles.

4. In a charge forming device for a multi-cylinder internal combustion engine having a plurality of spaced intake ports, an air manifold having a branch leading to each engine intake port and a common main air inlet, a spring closed valve in said main air inlet which is opened to admit air according to the depression in said manifold, a plurality of individual carburetors, each of which is provided with a constant level fuel chamber, said carburetors being supported by the manifold branches closely adjacent the engine intake ports and adapted to supply fuel to said branches close to said ports, a throttle valve in each manifold branch for controlling the flow therethrough, and common actuating means for said valves.

5. In a charge forming device for a multi-cylinder internal combustion engine having a plurality of spaced intake ports, an air manifold having a branch leading to each engine intake port and a common main air inlet, a spring closed valve in said main air inlet which is opened to admit air according to the depression in said manifold, a plurality of individual carburetors, each of which is provided with a constant level fuel chamber, said carburetors being cast integral with the manifold branches closely adjacent the engine intake ports and adapted to supply fuel to said branches close to said ports, a throttle valve in each manifold branch

for controlling the flow therethrough, and common actuating means for said valves.

6. In a charge forming device for a multi-cylinder internal combustion engine having a plurality of intake ports, an air manifold having a branch leading to each engine intake port and a common main air inlet, an automatically closed valve in said main air inlet which is opened to admit air according to the depression in said manifold, an individual primary carburetor supported by each manifold branch and adapted to supply an overrich mixture of fuel and air to each manifold branch, the amount of mixture supplied to each branch being approximately directly in accordance with the depression in said branches, a throttle valve in each manifold branch and common actuating means for said throttles.
7. In a charge forming device for a multi-cylinder internal combustion engine having a plurality of intake ports, an air manifold having a branch leading to each engine intake port and a common main air inlet, an automatically closed valve in said main air inlet which is opened to admit air according to the depression in said manifold, an individual primary carburetor supported by each manifold branch adjacent the engine intake port and adapted to supply an overrich mixture of fuel and air to each manifold branch close to said port, the amount of mixture supplied to each branch being approximately directly in accordance with the depression in said branches, a throttle valve in each manifold branch and common actuating means for said throttles.

In testimony whereof I hereto affix my signature.

HORACE W. ASIRE.
